[57] CLAIM

The ornamental design for a pancake or waffle maker die face, as shown and described.

DESCRIPTION

FIG. 1 is a front elevational view of a die face for a pancake or waffle maker die showing my new design therefor, all other parts of the pancake or waffle maker die being shown in phantom line and forming no part of my design; FIG. 2 is a cross section view taken along line 2—2 in FIG. 1; and,

FIG. 3 is a front elevational view of a die face for a pancake or waffle maker die showing another embodiment of my new design therefor.
